UNITED STATES PATENT OFFICE

2,363,565

GASHOLDER

John H. Wiggins, Chicago, Ill.

Application November 1, 1940, Serial No. 363,835

9 Claims. (Cl. 48—178)

This invention relates to apparatus of the general type disclosed in my prior United States Patents Nos. 2,050,405, 2,050,665, and 2,050,686, dated August 11, 1936, and No. 2,102,299, dated December 14, 1937. In apparatus of the kind described in said patents the gas space or chamber that holds the medium being stored, comprises a vertically-movable member that constitutes either the top or bottom of said gas space or chamber, a co-operating stationary member provided with a side wall and with a part that is arranged in opposed relation to said vertically-movable member, and a flexible element made of gas-tight fabric or other suitable flexible material attached to said movable and stationary members, so as to constitute an extensible side wall portion of the gas space that produces a gas-tight joint or connection between the vertically-movable member and stationary member and provides for the rise and fall of the vertically-movable member of the gas space. I have herein illustrated my present invention embodied in a gas holder of the general construction illustrated in my said prior Patent No. 2,102,299, but I wish it to be understood that many of the features of my present invention are applicable to and capable of being successfully embodied in an apparatus that is used for storing liquids and/or gases.

One object of my present invention is to provide an apparatus of the general type mentioned, in which the vertically-movable member of the gas space or storage chamber, is constructed in a novel manner that makes it well adapted for use in a large size apparatus having a gas space or storage chamber of relatively great diameter.

Another object is to provide an apparatus of the general type previously referred to, that is equipped with a counterweighting mechanism for the vertically-movable member of the gas space, housed completely within the apparatus and constructed so that it is not necessary to provide said vertically-movable member with holes or stuffing boxes for the chains or cables of the counterweighting mechanism.

Another object is to provide an apparatus of the kind last referred to, in which a housing for the counterweighting mechanism extends upwardly through the vertically-movable member of the gas space or storage chamber and constitutes a support for a stationary roof that may consist either of the top wall of the gas space, or a weather shield disposed above the vertically-movable member of the gas space.

Another object is to provide an apparatus of the general type previously mentioned, that is equipped with a novel means for preventing the flexible element or elements which provide for the rise and fall of the vertically movable member of the gas space, from freezing on or adhering to the side wall of the gas space or storage chamber.

Another object is to provide a novel means 10 for collecting or removing from the gas space or storage chamber, condensate that collects on the inner surface of the side wall of said chamber.

And still another object of my invention is 15 to provide means for preventing condensate that collects on the underside of the roof of the gas space from finding its way into the loop of the flexible element that is attached to the side wall and the vertically-movable part of the gas space 20 so as to provide for the rise and fall of said vertically-movable part. Other objects and desirable features of my invention will be herein-after pointed out.

Figure 1 of the drawing is a vertical trans- 25 verse sectional view of a gas holder constructed in accordance with my present invention.

Figure 2 is an enlarged vertical sectional view, 30 illustrating one form of construction that may be used to prevent the flexible element attached to the peripheral edge of the vertically-movable member of the gas space, from freezing on or adhering to the side wall of the gas space and for removing from said space condensate that collects on the side wall of same; and

Figure 3 is a vertical sectional view, illustrating another form of construction that may be used for the same purpose for which the construction shown in Figure 2 is employed.

In the drawing X designates the gas space of 40 a gas holder provided with a stationary cylindrical side wall A, a stationary roof or top B herein illustrated as being of substantially cone shape, and a bottom formed by a vertically-movable member or piston C, whose peripheral edge 45 is connected by means of a flexible, gas-tight element D with the side wall A of the gas space at the bottom edge of said side wall. The side wall A is arranged in an elevated position, i. e., at a point considerably above the surface of the 50 ground on which the apparatus is erected, and said side wall is sustained or supported by any suitable kind of a supporting structure E, which is of such height that the movable member or piston C of the gas space is capable of moving 55 downwardly a considerable distance below the

bottom edge of the side wall of the gas space X, as shown in Figure 1, thus producing a gas space of relatively great volume. The side wall A and the roof B are of gas-tight construction, but the supporting structure does not have to be gas-tight.

The piston C is combined with a counter-weighting mechanism that is housed in a novel manner on the interior of the apparatus, and which comprises a part that, in addition to serving as a supporting structure for the sheaves or pulleys of the counterweighting mechanism, also serves as a support for the central part of the roof B of the gas space. The part just referred to consists of a tubular member or cylinder F disposed vertically at the center of the gas space, and extending upwardly from the ground on which the apparatus is erected, to the central portion of the roof B that is attached to said tubular member. Due to the fact that the vertically-disposed roof supporting member F is arranged at the center of the gas space X, it is necessary to form a center opening in the piston C to receive said center member, and use a second flexible gas-tight element D' to produce and maintain a tight joint between said piston C and member F. Chains or cables 1 that are attached to the piston C, adjacent the center of same, lead upwardly from said piston over cables or sheaves 2 carried by the center tubular support F, and thence downwardly from said sheaves to a weight 3 that is arranged inside of and housed by the center tubular member F. In the form of my invention herein illustrated the chains or cables 1 are attached at one end to a collar 4 positioned some distance above the piston C and rigidly attached to the piston by any suitable means, as, for example, by a plurality of center posts 5 and radially-disposed tension rods 6 that impart the necessary strength and stiffness to the piston C to make it commercially feasible to embody my invention in a large size gas holder having a gas space of relatively great diameter. If necessary, the stationary roof B of the gas space may be reinforced and strengthened by truss rods 7 and struts 8, but the primary support of the roof consists of the tubular member F of the counterweighting mechanism that carries the chain pulleys and houses the chain weight of said counterweighting mechanism. As shown in Figure 1, the upper end of the tubular center support F is closed by a gas-tight cap 9, and said tubular center member is provided at its lower end with a gas-sealed drain device 10, which may consist of an inverted siphon.

One novel feature of my present invention consists in arranging the flexible element D at the peripheral edge of the piston C, in such relationship with the side wall A of the gas space, that there is no liability of said flexible element freezing on or adhering to said side wall. I attain this desirable result by attaching the upper end or outer edge of the sealing element D to an inwardly, off-set part at the lower end of the side wall A, said inwardly offset part being produced either in the manner shown in Figures 1 and 2, or in the manner shown in Figure 3. Thus, as shown in Figures 1 and 2, the side wall A may be provided at its lower end with an inwardly bent or offset portion A', to which the flexible element D is clamped, by a removable clamping bar 11, or the side wall A may be provided at its lower end with an angle A² welded or connected to the inner side of same in any

other suitable way and arranged with one of its legs or flanges disposed vertically, as shown in Figure 3, so as to constitute a surface to which the flexible element D can be detachably connected by a removable clamp 11^a. With either of the structures just described the flexible element D is prevented from touching the side wall A of the gas space on which condensate is liable to collect, and consequently, there is no liability of the flexible element D freezing on or adhering to the side wall of the gas space. Preferably, the apparatus is operated at zero, or a very slight positive pressure, say, plus $\frac{1}{2}$ " of water. Consequently, the flexible element D will hang plumb from the piston C, when the gas space is about one-half full. It is not necessary to construct the supporting structure E for the stationary side wall of the gas chamber so that the flexible element D will not touch or bear against said supporting structure, inasmuch as the supporting structure E is not gas-tight. When the supporting structure E is formed from a cylindrical shell, as herein shown, vents 12 are provided so as to cause the interior of said structure E to be open to the atmosphere, thereby eliminating condensation on the internal surface of the supporting structure E, with which the flexible element D may contact in the functioning of the apparatus. Gases are admitted to and withdrawn from the gas space by a conduit 18, in an apparatus of the kind herein described, wherein the piston C forms the bottom of the gas chamber and the stationary roof B forms the top wall of said chamber.

Another novel feature of the apparatus herein illustrated is that it is provided with means for automatically removing from the gas space X condensate that collects on the inner surface of the side wall A of said gas space. Said means may be constructed in the manner shown in Figure 2, or in the manner shown in Figure 3. In the form of my invention shown in Figure 2, the clamping bar 11, used to attach the flexible element D to the inwardly offset side wall portion of the gas space, is constructed or arranged so that it acts as a trough, on the interior of the gas space, that receives condensate which collects on and drains downwardly over the inner face of the side wall A of the gas space. Figure 2 shows the upper portion of the clamping bar 11 as being bent laterally slightly and provided with lugs 13 that cause said bar to be disposed in such relationship with the inwardly offset side wall portion of the gas space as to form a condensate trough on the interior of the gas space. At intervals around the circumference of the side wall A of the gas space, U-shaped outlet devices 14 are arranged so as to permit the condensate to escape from the trough above referred to, through holes 15 in the side wall of the gas space. The outlet devices or discharge devices 14 from the internal condensate trough of the gas space, are sealed with liquid 16, as shown in Figure 2. In the alternative construction used to attach the flexible element D to the side wall portion of the gas space, and illustrated in Figure 3, the angle A² serves as a trough that receives condensate which collects on and drains downwardly on the inner face of the side wall of the gas space, said trough having discharge outlets 14 of the kind previously mentioned. It is preferable to construct the apparatus in the manner illustrated in Figure 3, due to the fact that this form of construction overcomes the necessity of bending or deforming the side wall

plates of the gas chamber, it permits flat strips of metal to be used for the clamping bar 11, and it causes the flexible element D to hang clear of the supporting structure E when the piston C is in its lowermost position, assuming, of course, that the apparatus is operated at or very near zero pressure gauge inside of the gas space.

In order to prevent condensate from dripping from the roof B of the gas space into the fold or loop of the flexible element D, I attach a vane 17 to the underside of the said roof at such a point that condensate on the under surface of the roof B will flow downwardly over same to the vane 17 and then drip downwardly from same onto the top side of the piston C, the vane 17 being disposed out of vertical alignment with the loop or fold of the flexible element D, as shown in Figure 1, or in other words, disposed at a point some distance inwardly from the point at which the inner edge of the flexible element D is attached to the piston C. The slight quantity of condensate that may find its way onto the top side of the piston C will evaporate without causing any damage or interfering with the proper functioning of the apparatus. The reference character 18 designates a combined gas inlet and outlet.

In order that the apparatus may be operated at the same pressure in all positions of the piston C, the chains or cables 1 of the counterweighting mechanism are designed so that the weight of same is substantially equal to the weight of the flexible elements D and D'. Since the weight of the flexible elements D and D' increases as the piston C rises, the internal pressure must decrease as the piston rises. But as the weight 3 moves downwardly, the increasing weight of the chains 1 balances the increasing weight of the flexible elements D and D'. Thus, by adding weights along the length of the chains or cables 1, or by making the weight per foot of said chains or cables the same as the weight per foot of the flexible elements D and D', the apparatus will operate at the same pressure in all positions of the piston C.

Having thus described my invention, what I claim as new and desire to secure by Letters Patent is:

1. In an apparatus provided with a gas storage space or chamber having a stationary side wall, the combination of a vertically-movable member that forms one horizontally-disposed wall of said gas space, a stationary roof arranged above said vertically-movable member, a supporting member for said roof extending upwardly through an opening in said vertically-movable member, gas-tight, flexible diaphragms attached to said vertically-movable member and to said side wall and roof supporting member so as to provide for the rise and fall of said vertically-movable member, and a counterweight for

said vertically-movable member operatively connected with same and housed by said roof supporting member.

2. An apparatus of the kind described in claim 1, in which the roof supporting member is of tubular form and the counterweight is arranged to travel vertically inside of said member.

3. An apparatus of the kind described in claim 1, in which the counterweight is connected with the vertically-movable member by flexible devices, and sheaves or pulleys, over which said flexible devices travel, mounted on said roof supporting member adjacent the upper end of same.

4. An apparatus of the kind described, comprising a gas storage space or chamber provided with a stationary side wall, a vertically-movable member whose position is adapted to change to vary the volume of the gas storage space, a gas-tight, flexible diaphragm attached to said member and to the side wall of the gas storage space, a top wall for said gas storage space, and a collection trough arranged inside of the gas storage space at the lower end of said side wall and disposed so as to collect condensate that drains downwardly on the inner face of the side wall of the gas storage space.

5. An apparatus of the kind described in claim 4, provided with a discharge outlet for said collection trough, and a liquid seal for said discharge outlet.

6. An apparatus of the kind described in claim 4, in which said collection trough extends circumferentially around the lower end portion of the side wall of the gas space, and means for permitting the condensate to escape from said trough at a plurality of points.

7. An apparatus of the kind described in claim 4, in which the collection trough at the lower end of the side wall of the gas storage space is provided with an inwardly offset portion to which said diaphragm is attached.

8. A gas holder having a gas storage space provided with a stationary side wall, a vertically-movable piston that constitutes the bottom of the gas space, a roof that constitutes the top of the gas space, a supporting member for said roof projecting upwardly through a center opening in said piston, gas-tight, flexible diaphragms attached to the piston and to said side wall and roof supporting member, and means for collecting and discharging from the gas space condensate that drains down the inner face of the side wall of the gas space.

9. An apparatus of the kind described in claim 4, provided with means for causing condensate on the underside of the top wall of the gas space to be diverted from the side wall of said gas space and discharged onto said vertically-movable member.

JOHN H. WIGGINS.
